CABLE FLOOR STRUCTURE WITH OFFSET CONNECTORS
 Oliver C. Eckel, Carlisle, Mass.
 (155 Fawcett St., Cambridge 38, Mass.)
 Filed Aug. 8, 1961, Ser. No. 130,107
 7 Claims. (Cl. 94—30)

This invention relates to a cable floor structure with connectors that are offset.

One object of my invention is to provide a floor formed of cables that are attached to offset connectors which extend through I-beam holes that are in diagonal relationship to each other, whereby the stress on the I-beams is uniformly distributed and the floor cables provide a level floor.

Another object is to provide aligning bars for said floor structure having holes in horizontal alignment through which offset cable connectors extend, thus holding the floor cables in one plane and under a straight pull, thereby avoiding undue wear of different parts where they intersect or connect.

A further object is to provide such a floor structure that is simple to manufacture, relatively easy to install and is unusually durable.

The foregoing and other objects which will appear as the nature of the invention is better understood, may be accomplished by a construction, combination and arrangement of parts such as is disclosed by the drawings. The nature of the invention is such as to render it susceptible to various changes and modifications, and therefore, I am not to be limited to the construction disclosed by the drawings nor to the particular parts described in the specification; but am entitled to all such changes therefrom as fall within the scope of my claims.

In the drawings:

FIG. 1 is a top plan view showing my floor structure.

FIG. 2 is an enlarged, fragmentary, top plan view of said floor structure.

FIG. 3 is an enlarged, fragmentary, perspective view of my floor structure.

FIG. 4 is a side elevational view, showing the tensioning means of my floor structure connected to an I-beam at one end and to a floor cable at the other end.

FIG. 5 is a side elevational view showing the main supporting means of my floor structure.

FIG. 6 is a sectional view taken on the line 6—6 of FIG. 5.

As illustrated, my floor structure has well-known main supporting means 7 having upright I-beams 8 and horizontal I-beams 10. The latter each has a front flange 12, a web 14 and a rear flange 16. Said front flange 12 has holes 18 therethrough, spaced laterally from each other, at opposite sides of said web 14, thus being above and below said web.

Connectors 20, shown as hook bolts, each has an elongate or rod portion 22 extending through said holes 18 and which is offset. It is screw-threaded at one end, and has a hook portion 24 at the other end. The offset portion is between said front flange 12 and an aligning bar 34, later described.

Movably mounted on each said rod portion 22, at the rear side of said front flange 12, is a coil spring 26. There are washers 28 and 30 at opposite ends of said rod portions 22, and a bearing member or retainer shown as a nut 32 screw-threadedly connects on the rear end portion thereof to thereby retain said coil spring under compression between said front flange 12 and said nut 32. Said connectors 20, coil springs 26 and associated parts constitute the tensioning means for my floor structure.

Aligning bars 34 extend between opposite sides of

2

said floor structure, four being shown. These bars are unattached, hence may be said to float. Each said bar 34 has noles 36 therethrough which are in horizontal alignment as shown. Said connector rod portions 22 extend through said bar holes 36, those that are above said I-beam web 14 being offset so as to extend from said front flange 12 downwardly to enter said holes 36. Those that are below said web are offset so as to extend from said front flange upwardly to enter said holes 36. The metal or other material forming said rod portions 22 may be bent and hardened to achieve this offset shape.

The main area of my floor structure is formed of wire cables 40 one end of each having fastening means shown as a loop 42 which extends around a thimble 44. A clamp 46 makes said wire cable fast by firmly clamping the cable end with the adjacent part of the cable beyond said loop 42.

Said hook portions 24 extend into said loops 42 to thus make the desired connections and thus maintain all of said cables evenly to thus achieve a level floor without strain or distortion.

As shown in said FIG. 1 said cables 40 extend from four sides of the room, hence, in this instance, they cross each other, and in the usual woven or under-and-over arrangement.

My floor structure is used for persons to walk upon. It is especially adapted for use in chambers where absence of echo is required. It provides no surface from which sound waves can be reflected in the audio frequency range. Such chambers are used in the calibration of microphones, loud speakers and other apparatus.

What I claim is:

1. Floor structure comprising main supporting means embodying I-beams extending horizontally at opposite sides of said structure each having a front flange, a rear flange and a web between said flanges, said front flange having upper holes and lower holes above and below said web respectively and spaced laterally from each other, connectors at opposite sides of said structure each embodying an elongate, offset rod portion, a hook portion at one end of the latter and bearing means spaced from said hook portion, said rod portions extending through said upper and lower flange holes at opposite sides of said structure towards each other, two aligning bars having holes therethrough in lateral alignment, said offset portions of said rods commencing between said bars and said front flanges and passing through said aligning bar holes, floor cables extending laterally of said structure and connected to said hook portions, and coil springs around said rod portions bearing against the rear faces of said front flanges, and said bearing means.

2. Floor structure comprising main supporting means embodying I-beams extending horizontally at opposite sides of said structure each having a front flange, a rear flange and a web between said flanges, said front flange having upper holes and lower holes above and below said web respectively and spaced laterally from each other, connectors at opposite sides of said structure each embodying an elongate, offset rod portion, a hook portion at one end of the latter and a bearing member at an end portion opposite said hook portion, said rod portions extending through said upper and lower flange holes at opposite sides of said structure, two aligning bars unattached to said main supporting means and having holes therethrough in lateral alignment, said offset rod portions extending towards each other and passing through said aligning bar holes, floor cables extending laterally of said structure and connected to said hook portions, and coil springs around said rod portions, and bearing against the rear faces of said front flanges, and said bearing members.

3. Floor structure comprising main supporting means embodying I-beams extending horizontally at opposite sides of said structure each having a front flange, a rear flange and a web between said flanges, said front flange having upper holes and lower holes above and below said web respectively and spaced laterally from each other, connectors at opposite sides of said structure each embodying an elongate offset rod portion threaded at one end, a hook portion at another end of the latter, and a threaded nut at an end portion opposite said hook portion, said rod portions extending through said upper and lower flange holes at opposite sides of said structure towards each other, two aligning bars having holes therethrough in lateral alinement, said offset rod portions extending towards each other and passing through said aligning bar holes, floor cables extending laterally of said structure and connected to said hook portions, and coil springs around said rod portions bearing against the rear faces of said front flanges and said nuts.

4. Floor structure comprising main supporting means embodying I-beams extending horizontally at opposite sides of said structure each having a front flange, a rear flange and a web between said flanges, said front flange having upper holes and lower holes above and below said web respectively and spaced laterally from each other, connectors at opposite sides of said structure each embodying an elongate offset rod portion, a hook portion at one end of the latter and a bearing member spaced from said hook portion, said rod portions extending through said upper and lower flange holes at opposite sides of said structure, two aligning bars having holes therethrough in lateral alinement, said offset rod portions extending towards each other and passing through said aligning bar holes, and floor cables extending laterally of said structure having loops at opposite ends connected to said hook portions, and coil springs around said rod portions bearing against the rear faces of said front flanges, and said bearing members.

5. Floor structure comprising main supporting means embodying I-beams extending horizontally at opposite sides of said structure each having a front flange, a rear flange and a web between said flanges, said front flange having upper holes spaced from each other and in horizontal alinement and above said web, and lower holes spaced from each other and in horizontal alinement and below said web, connectors at opposite sides of said structure each embodying an elongate, offset rod portion extending through said upper and lower flange holes at opposite sides of said structure, a bearing member on said rod portion spaced from an end thereof, two aligning bars having holes therethrough in lateral alinement, said offset rod portions extending towards each other and passing through said aligning bar holes, floor cables extending laterally of said structure between and connected

to said rod portions, and coil springs around said rod portions bearing against the rear faces of said flanges and said bearing member.

6. Floor structure comprising main supporting means embodying I-beams extending horizontally at four sides of said structure in angular relationship to each other and each having a front flange, a rear flange and a web between said flanges, said front flange having upper holes and lower holes above and below said web respectively and spaced laterally from each other, four connectors at said four sides of said structure each embodying an elongate offset rod portion, a hook portion at one end of the latter and a bearing member at an end portion opposite said hook portion, said rod portions extending through said upper and lower flange holes at said four sides of said structure, four aligning bars unattached to said main supporting means and having holes therethrough in lateral alinement, each pair of said offset rod portions extending towards each other and passing through said aligning bar holes, floor cables extending laterally of said structure in angular relationship and connected to said hook portions, and coil springs around said rod portions bearing against the rear faces of said front flanges and said bearing members.

7. Floor structure comprising main supporting means embodying I-beams extending horizontally at four sides of said structure in angular relationship to each other and each having a front flange, a rear flange and a web between said flanges, said front flange having upper holes and lower holes above and below said web respectively and spaced laterally from each other, four connectors at said four sides of said structure each embodying an offset rod portion, a hook portion at one end of the latter and a bearing member at an end portion opposite said hook portion, said rod portions extending through said upper and lower flange holes at said four sides of said structure, four aligning bars having holes therethrough in lateral alinement, each pair of said offset rod portions extending towards each other and passing through said aligning bar holes, floor cables extending laterally of said structure in angular relationship and connected to said hook portions, and tensioning means connected to said rod portions and said supporting means to hold said cables under tension.
